AUXILIARY SUPPORT FOR WATER SKIERS

George T. Roberts, Ferndale, Mich.

Application March 27, 1953, Serial No. 345,100

4 Claims. (Cl. 9—21)

This invention relates to water skiing and more particularly to an auxiliary support adapted to be secured to the tow vessel and used by the water skier to enable the skier to assume the planing position easily and safely.

The popularity of water skiing is ever increasing but it is considered that the sport is kept from achieving its full popularity through the difficulties encountered by the skier in changing from the static pick-up position to the high velocity planing or skiing position.

Heretofore it has been customary for the water skier to don his skis and stand in shallow water with his skis resting on the bottom of the lake or the like. The tow vessel is brought in close to the shore and the tow rope grasped by the skier. The tow vessel then proceeds to get under way, dragging the skier behind. It is at this critical point, where the speed of the vessel and the skier are slow, that water skiing is most difficult. The forward motion of the tow vessel is transmitted to the skier via the tow rope and has a tendency to upset him because of the drag on the skis on the bottom of the lake. If the skier is successful in getting off the bottom, he still has a tendency to upset because the pull of the tow rope coupled with the drag of the submerged skis tends to somersault the skier. The skier must overcome the tendency to somersault by leaning rearwardly and elevating the forward portions of his skis so that he will rise to surface of the water and his skis will plane over the surface. This necessary procedure is the only certain way to assume the planing position and can be executed successfully only after considerable experience. The inexperienced water skier is subjected to the unfamiliar forces exerted by the skis, the water, and the tow vessel and finds himself subjected to these forces at an ever increasing speed which frequently produces confusion and consternation in the mind of the novice with the result that he becomes panicky and loses control over his skis, with the almost inevitable conclusion of upset. Once the novice has been subjected to a violent upset it is small wonder that his interest in water skiing wanes.

With the foregoing in view it is an object of this invention to provide an auxiliary support which is attachable to a tow vessel and which provides support for a water skier during the initial stages of getting under way.

Another object of the invention is to provide an auxiliary support which aids the skier in assuming the planing position.

Another object of the invention is to provide an auxiliary support which does not interfere with the skier when he leaves the support.

Another object of the invention is to provide an auxiliary support which causes no appreciable drag on the towing vessel.

Another object of the invention is to provide an auxiliary support which can be attached to either an inboard or outboard motor boat without modification of either the boat or the support.

A further object of the invention is to provide an auxiliary support having means enabling it to be connected

2

to a tow vessel without danger of injury to the skier or the support.

A further object of the invention is to provide an auxiliary support for water skiers which is capable of being folded into a compact unit for ease of transportation and storage.

A further object of the invention is to provide an auxiliary support which is simple and inexpensive to manufacture but which is rugged and durable in construction.

10 These and further objects and advantages of the invention will be specifically pointed out or will become apparent from a reading of the specification when considered in conjunction with the accompanying drawing wherein:

Fig. 1 is a perspective view of the novel auxiliary support showing it as it would appear when connected to a towing vessel.

15 Fig. 2 is a plan view of the support as shown in Fig 1;

Fig. 3 is a side elevational view of the support;

20 Fig. 4 is a side view, partially in cross-section, of the connection of the support to the rear of a tow vessel;

Fig. 5 is a cross-sectional view taken on the line 5—5 of Fig. 4; and

Fig. 6 is a cross-sectional view taken on the line 6—6 of Fig. 3.

25 Referring now to the drawing wherein like numerals represent like and corresponding parts throughout the several views, the embodiment of the invention shown therein for illustrative purposes comprises what is herein termed a glider 10 pivotally connected to a pair of draw bars 11 which in turn are hingedly connected to a tow vessel 12.

30 More particularly, the glider 10 is essentially a modified water ski having a superstructure mounted thereon on which a water skier may be supported. The support 10 consists of a runner 13 having a bowed upwardly leading edge 14 which is apertured as at 15 for reception of a pivot pin or bolt 16. The runner 13 has secured thereto a number of studs 17 which are secured to and support an elongated seating deck or board 18 directly above runner 13. Deck 18 is apertured as at 19 at its forward end for reception of pin or bolt 16.

35 A pair of draw bars 11 are positioned one above the other and are apertured adjacent their rear ends 20 as at 21 for reception of bolt 16. It will be observed that bolt 16 passes through both draw bars 11, deck 18 and runner 13 enabling the bars and the support to pivot relative to each other. The elements of the structure are maintained in proper relationship by the head 22 of bolt 16 and a nut 23 threaded on the end of the bolt. To provide a firm connection and to eliminate wear on the under side of runner 13 a substantially triangular block 24 is interposed between runner 13 and nut 23. In connecting the two bars, the deck, and the runner together by the single pin or bolt 16, the connection is not tight and rigid but is rather loose so that there is sufficient play between the head 22 of bolt 16 and deck 18 to permit the bars 11 to move up or down with respect to the deck but there is insufficient play to permit the block 24 to turn.

40 When the auxiliary support is to be attached to a tow boat, the forward ends 21 of the bars 11 are spread to a width approximating the width of the boat. The ends of the arms are slotted as at 25 for reception of the eye sections of eye-bolts 27. Two eye-bolts 27 are provided, one at each side of the rear of the boat 12, or as widely spaced as practicable, to provide a stable, three point connection which precludes the possibility of the auxiliary support tipping. The spreading of the arms 11 enables an outboard motor (not shown) to be mounted on the rear of the boat in the usual manner without interference from the support 10 or the arms 11.

45 To prevent the bars 11 from becoming unconnected from the eye-bolts 27, a pair of anchor links are pro-

vided, each of which comprises a headed bolt 29 equipped with a washer 30 adjacent the head and another washer 31 adjacent the nut 32. The bolt 29 is of sufficient length to span the arm 11 and the washers 30, 31 are disposed between the head and nut, respectively, and the sides of the arm 11 with the bolt itself lying atop arm 11 and inserted through the eye of the eye-bolt 27. This construction permits the arms to hinge about the eye-bolts but positively prohibits the arms from pulling free from the eye-bolts.

When it is desired to connect the auxiliary support to a tow vessel, the arms 11 are secured to the rear of the vessel so that the glider lies astern. The glider will assume the position illustrated in Fig. 3 and will sink substantially no farther in the water. This antisinking feature is an important feature of the invention and is accomplished by the binding action between the bolt 16 and the ends 20 of arms 11 abutting the top of deck 18. The depth to which the glider initially stands in the water is controlled by the length of the ends of the arms 20 which extend rearwardly of the apertures 19. In the embodiment illustrated, the ends 20 extend a sufficient length that the glider is approximately half submerged when the tow vessel is standing still.

The water skier seats himself on the glider 10 with his skis 33 on either side and submerged to whatever depth he desires. The skier may either hold onto the deck 18 or to the tow rope (not shown) which will be secured to the boat. The skier will receive total support from the auxiliary support 10 so it is unnecessary for him to start in shallow water with his skis on the bottom of the lake. As the tow boat gets under way, the auxiliary support will itself begin to plane raising the skier farther out of the water. Further speed will enable the skier to support himself on his skis 33 which need never be very deep in the water and as the speed of the tow vessel increases the skier may gradually raise himself from the deck 18 until finally his entire weight is borne by his skis 33. At this point the tow rope may be payed out so that the skier will be at a proper distance behind the tow vessel.

As the weight of the skier is removed from the auxiliary support it is conceivable that rough or choppy water could flip the auxiliary support counterclockwise about its hinged connection to the tow vessel and cause injury to the water skier. To eliminate this possibility the ends 21 of draw bars 11 are sufficiently long so that upon rotation they will engage the upper portion of the tow vessel 12 and, in cooperation with the eye-bolt 27 and the bolt 29, preclude the support from flipping upwardly a distance sufficient to cause injury.

Although the amount of hinging about eye-bolts 27 is limited, there is sufficient free travel that the glider may rise and plane along the surface of the water so that the support creates no appreciable drag on the tow vessel.

When the skier desires to remove the auxiliary support from the tow vessel, it is a simple matter to remove the bolts 29 and disconnect draw bars 11 from the eye-bolts 27. The draw bars 11 may then be pivoted so as to lie along deck 18 to make a compact unit which conveniently may be transported and stored.

The auxiliary support disclosed herein provides a firm support for a skier so that he is not subjected to the combination of forces which violently tend to upset him. When using the auxiliary support the skier is required to merely keep his skies parallel and pointed slightly upwardly so they will begin to plane when the rate of travel through the water is sufficiently fast. By the elimination of the forces adversely affecting the skier the feeling of apprehension is largely dissipated and even the most inexperienced water skier may enjoy the sport. One especially significant feature of the invention is the elimination of the necessity of the tow vessel returning to shallow water to "pick-up" the skier. Should the skier lose his balance while in deep water, the tow vessel need only return to the locality of the fall. The skier may then board the support and begin again without having to wait while the vessel returns to a shallow spot so that the skier may stand upright.

Although but one embodiment of the invention has been shown and described in detail, it is obvious that many changes may be made in the shape, size, detail, and arrangement of the various elements within the scope of the subjoined claims.

I claim:

1. In combination a tow vessel having a tow device for a water skier leading from said vessel, laterally spaced tow points on said vessel, paired tow bars connected to said tow points extending rearwardly outwardly of said vessel and converging toward one another so as to connect at the extending ends at an apex forming a triangulated side wise inflexible tow point rearwardly outwardly of said vessel, and an auxiliary ski connected to both said tow bars at their extending apex; said auxiliary ski being positioned to provide the water skier with a hand grip to aid the skier in attaining an upright position during the initial starting period.
2. In a device as to assist a water skier to attain a planing position on his skis behind a tow vessel, paired tow bars adapted to be attached at one end of each bar at laterally spaced points on the stern of the vessel with said bars converging to an apex connected to each other rearwardly outwardly of the vessel forming a sidewise inflexible tow point outwardly rearwardly of the vessel and an auxiliary ski connected to said tow bars at their connected apex; said auxiliary ski being suitable to provide a hand grip for a water skier to assist a water skier in attaining buoyancy and balance at the initiation of towing.
3. In a device as set forth in claim 2, a superstructure on said auxiliary ski providing an elevated hand grip for the water skier.
4. In a device as set forth in claim 2, said tow bars being pivotally mounted in a vertical plane.
